ROTARY HAMMER DRILL

1,845,074

Filed Aug. 20, 1930

UNITED STATES PATENT OFFICE

GUSTAVIS ADOLPHIS BILLSTROM, OF READ, COLORADO

ROTARY HAMMER DRILL

Application filed August 20, 1930. Serial No. 476,683.

This invention is a novel improvement in rotary hammer drills and the principal object of the invention is to provide a rotary hammer drill particularly adapted for oil and water well drilling and for mineral and mine tests and the like, my novel drill being adapted to take the place of the rotary drills now in use and being adapted to drill a core readily and efficiently through any stratum or rock which it may encounter in such drilling operation.

A further object of the invention is to provide a combined hammer and rotary drill in which the hammer is positively rotated and in turn rotates by friction the drill bit by reason of complementary ratchet teeth on the hammer and bit, the teeth of the hammer sliding over the teeth of the bit when the rotatable bit is held stationary or rotation sufficiently retarded by engagement of the bit in the ground, the overriding of the hammer teeth raising the hammer and storing up energy in an energy storing device to augment the weight of the hammer on the next succeeding downstroke of the hammer when the teeth re-mesh, thereby delivering a strong impact upon the entire cutting head of the bit, and eliminating twist-off of either the bit or drill stem.

Other minor objects of the invention will be hereinafter set forth.

I will explain the invention with reference to the accompanying drawings which illustrates several practical embodiments thereof to enable others familiar with the art to adopt and use the same; and will summarize in the claims the novel features of construction, and novel combinations of parts, for which protection is desired.

In said drawings;

Fig. 1 is a longitudinal section through one form of my novel rotary hammer drill showing the hammer in normal position.

Fig. 2 is a similar longitudinal section through a modified form.

Fig. 3 is a sectional view showing the hammer in raised position and the ratchet teeth of the hammer on the point of sliding over the upper ends of the teeth on the bit, to

permit a blow by the hammer on the cutting head of the bit.

Fig. 4 is a section on the line 4—4 Fig. 3.

As shown my invention comprises a block 1 of suitable weight, shape and proportions slightly reduced in diameter at each end forming a central annular shoulder, the reduced portions being externally threaded. Block 1 is provided with a central bore 1a extending entirely through the block which bore is tapped at its upper end to receive the threaded lower end of a pipe 3. Threaded onto the lower end of block 1 is a drill bit 2 of any desired type having an internally threaded annular flange 2a on its upper end adapted to engage the threaded lower end of block 1. Bit 2 is also provided with an axial bore 2b which registers with bore 1a of block 1. Threaded onto the upper end of block 1 is a cylindrical casing 4 housing the pipe 3, the block 1, bit 2, pipe 3, and casing 4 rotating as a unit. Upon the upper end of block 1 within the casing 4 are raised annularly arranged ratchet teeth 1b, one face of each of the teeth 1b being cut vertically or parallel with the axis of pipe 3.

Above block 1 within casing 4 is a slidably rotating hammer 5, having an axial bore 5a loosely receiving pipe 3, and having a reduced lower end 5b of diameter slightly less than the internal diameter of the annular teeth 1b on block 1, said reduced end 5b being adapted to fit within teeth 1b and strike a blow upon the upper end of the block 1 as hereinafter described. Around the reduced portion 5b of hammer 5 are annularly disposed ratchet teeth 5c corresponding with and complementary to the ratchet teeth 1b on block 1, the said teeth 5c and 1b being normally in engagement, but when hammer 5 is rotated in the direction of the arrow—Figs. 1, 2, 3 with respect to block 1 the cam action of the ratchet teeth 5c sliding over teeth 1b will lift hammer 5 away from block 1 until teeth 5c run over the tops of their related teeth 1b at which time hammer 5 will drop down again to strike a blow upon block 1 due to the action of springs 9 and the perpendicularity of one face of each of said teeth. Preferably the tips of teeth 5c lie slightly above

the end of reduced portion 5b so that the hammer impact will be delivered by portion 5b upon the center of block 1 within the ratchet teeth 1b instead of being delivered by teeth 5c upon teeth 1b.

The upper end of hammer 5 is slightly reduced in diameter as at 5d to receive the open end of a cylindrical cap 6 which cap is adapted to telescope the hammer 5. The closed upper end 6a of cap 6 is provided with a tapped central bore which receives the lower threaded end of the main or upper rotating pipe 7 whereby as pipe 7 is rotated the cap 6 will likewise be rotated. The lower pipe 3 extends upwardly from block 1 through hammer 5, through cap 6, and enters into the lower end of pipe 7, pipe 3 being slightly smaller in diameter than pipe 7. Rotation of pipe 7 does not necessarily rotate pipe 3 and block 1, the block 1 being rotated as hereinafter described. The cap 6 is provided adjacent its lower open end with two sets of diametrically opposed longitudinal slots 6b adapted to engage four studs 5e tapped into the side of hammer 5 adjacent its upper end whereby hammer 5 is permitted to telescope the cap 6 a distance sufficient to permit its ratchet teeth 5c to override the ratchet teeth 1b of block 1, while causing hammer 5 to be positively rotated by and with pipe 7 by means of cap 6. Hence pipe 7, cap 6, and hammer 5 always rotate together as a unit. The heads of studs 5e preferably lie substantially flush with the outer periphery of cap 6 so as to form a smooth outer surface for cap 6 which rotates within the cylindrical casing 4.

Threaded into the upper end of the cylindrical casing 4 is a bearing block 8 provided with a central bore 8a for the passage therethrough of pipe 7, the ends of the bore 8a being countersunk to form tapered bearing seats 8b into the upper one of which enters an annular tapered shoulder 7a formed upon the pipe 7, shoulder 7a seating in the top bearing seat 8b and carrying the entire weight of pipe 7. A similar annular tapered shoulder 6c is provided on the head 6a of cap 6 surrounding pipe 7, which shoulder 6c engages the lower tapered bearing seat 8b in the bearing block 8.

As shown in Figs. 1 and 3 within cap 6 and around pipe 3 between the head 6a and hammer 5 is a coiled spring 9. If desired a buffer plate 6d may be inserted between spring 9 and hammer 5. As the hammer 5 is moved upwardly in the casing 2 as hereinafter described spring 9 will be compressed as in Fig. 3 storing up energy to drive the hammer 5 downwardly when the ratchet teeth 5c of hammer 5 slide over the tops of the teeth 1b of block 1.

In Fig. 2 a modification is shown in which spring 9 is replaced by a compressible casing 9a, said casing being annular in shape and fitting around pipe 3 and having a valve stem

9b passing through the head 6a of cap 6 which stem may be provided with the usual valve 9c, whereby the casing may be charged with air or other compressible fluid. The compressible fluid casing 9a operates in substantially the same manner as the spring 9.

The upper end of casing 4 is closed by a head 10 having a bore 10a and a stuffing box 11 surrounding pipe 7.

In assembling the rotary hammer drill, bit 2 is threaded onto the lower end of block 1, and pipe 3 threaded into the upper end of block 1; casing 4 is then threaded onto the upper end of block 1 over the ratchet teeth 1b. Spring 9 or the compressible casing 9a is then placed into the cap 6 with the valve 9a extending through the head 6a and hammer 5 inserted into cap 6. The holes for the studs 5e of the hammer should then be aligned with the enlarged holes at the lower end of slots 6b of cap 6, and screws 5e inserted and screwed down until the head of the screws lie within the walls of cap 6 and the bolt heads are in line with the slots 6b. The air sack 9a should then be pumped to whatever pressure needed to strike the proper blow, governed by the hardness of the rock. Then assemble the bearing block 8 by placing the bearings into the block and insert block 8 against the bearing 6c of the head 6a of cap 6 and extend drive pipe 7 through the bearing block 8 and screw the pipe into cap 6 until the shoulder 7a on pipe 7 rests against the upper bearing seat 8b. Place members 5, 6, 7 and 8 into casing 4 and screw bearing block 8 to the bottom of the threads in casing 4; then slip head 10 over pipe 7 and screw into casing 4. Pack stuffing box 11 on head 10 and screw into place around pipe 7. The machine is now ready for drilling.

The machine is then lowered into the bottom of the well and operates as follows; the cutting edges of the drill bit 2 take hold of the bottom of the well and hold the bit 2, and block 1 with its ratchet in an initial stationary position. The drive pipe 7 is then revolved in the direction of the arrow Fig. 1 and cap 6 and hammer 5 are accordingly rotated. The ratchet teeth 5c on hammer 5 tend to climb over the ratchet teeth 1b on block 1 which raises hammer 5 upwardly and compresses the air casing 9a or spring 9. As teeth 5c slide over teeth 1b the hammer 5 is forcibly driven down against the head of block 1, transferring the blow to the drill bit 2, causing the cutting edges to penetrate the bottom of well. The friction of the ratchet teeth 5b which is exerted on the ratchet teeth 1b of block 1 causes the entire assembly to rotate as it cuts until bit 2 is restrained from rotation due to its engagement with the ground; and immediately the hammer is raised and a blow impacted upon the block 1 of the bit which should dislodge the bit or free same from its restraining element.

The usual water circulation passes through pipes 7 and 3 at the center of the assembly and passes out through the holes 2b in the bottom of drill bit 2 removing the cuttings.

5 I do not limit my invention to the exact forms shown in the drawings for obviously changes may be made therein within the scope of the claims.

I claim:

10 1. A rotary hammer drill, comprising a drill bit; a hammer member slidably and rotatably mounted with respect to the bit, a cap having a splined engagement with the hammer; means for preventing separation of the drill bit and cap; means for rotating the cap; a compressible member within the cap; and normally engaging ratchet teeth on the bit and hammer for rotating by friction the bit with the hammer, and for permitting overrunning of the hammer teeth upon restrained rotation of the drill bit to raise the hammer and compress the compressible member thereby augmenting the weight of the hammer on its down stroke when the teeth 25 re-engage.

2. In a drill as set forth in claim 1; said ratchet teeth being annularly arranged, and a reduced end on the hammer disposed centrally of its teeth adapted to engage the bit 30 centrally of its teeth when the teeth are engaged.

3. In a drill as set forth in claim 1, said compressible member comprising a coiled spring above the end of the hammer within 35 the cap.

4. In a drill as set forth in claim 1, said compressible member comprising a compressible fluid chamber above the end of the hammer within the cap; and valve means for 40 filling the chamber.

5. A rotary hammer drill, comprising a drill bit having a bore; a fixed pipe in said bore; a hammer member slidably and rotatably mounted on said pipe above the bit; a cap around the upper end of said hammer having a splined engagement therewith; means for preventing separation of the drill bit and cap; a rotary drive pipe for rotating the cap, the fixed pipe loosely entering 50 the lower end of the drive pipe; a compressible member within the cap; and normally engaging ratchet teeth on the bit and hammer for rotating by friction the bit with the hammer, and for permitting overrunning of 55 the hammer teeth upon restrained rotation of the drill bit to raise the hammer and compress the compressible member, thereby augmenting the weight of the hammer on its down stroke when the teeth re-engage.

60 6. In a drill as set forth in claim 5; said ratchet teeth being annularly arranged, and a reduced end on the hammer disposed centrally of its teeth adapted to engage the bit 65 centrally of its teeth when the teeth are engaged.

7. In a drill as set forth in claim 5; said compressible member comprising a coiled spring above the end of the hammer within the cap.

8. In a drill as set forth in claim 5, said compressible member comprising a compressible fluid chamber above the end of the hammer within the cap; a stem on the chamber extending through cap; and a valve in said stem.

9. A rotary hammer drill comprising a drill bit; a cylindrical casing secured to the upper end of said bit; a cylindrical hammer slidably and rotatably mounted within the casing; a cap around the upper end of said hammer having a splined engagement therewith; a bearing in the upper end of the casing for preventing separation of the drill bit and cap; means for rotating the cap; a compressible member within the cap; and normally engaging ratchet teeth on the bit and hammer for rotating by friction the bit with the hammer, and for permitting overrunning of the hammer teeth upon restrained rotation of the drill bit to raise the hammer and compress the compressible member, thereby augmenting the weight of the hammer on its down stroke when the teeth re-engage.

10. In a drill as set forth in claim 9; said ratchet teeth being annularly arranged, and a reduced end on the hammer disposed centrally of its teeth adapted to engage the bit 95 centrally of its teeth when the teeth are engaged.

11. In a drill as set forth in claim 9, said compressible member comprising a coiled spring above the end of the hammer within the cap.

12. In a drill as set forth in claim 9, said compressible member comprising a compressible fluid chamber above the end of the hammer within the cap; a stem on the chamber extending through cap; and a valve in said stem.

13. A rotary hammer drill comprising a drill bit; a cylindrical casing secured to the upper end of said bit; a cylindrical hammer slidably and rotatably mounted within the casing; a cap around the upper end of said hammer having a splined engagement therewith; a bearing in the upper end of the casing for maintaining the cap and drill bit in fixed relation; a driving member extending down through the bearing for rotating the cap; a tapered shoulder on said driving member engaging a tapered bearing seat in the block for supporting the driving member; a compressible member within the cap; and normally engaging ratchet teeth on the block 110 and hammer for rotating by friction the bit with the hammer, and for permitting overrunning of the hammer teeth upon restrained rotation of the drill bit to raise the hammer and compress the compressible member, thereby augmenting the weight of the hammer on its down stroke when the teeth re-engage.

120 14. In a drill as set forth in claim 13; said ratchet teeth being annularly arranged, and a reduced end on the hammer disposed centrally of its teeth adapted to engage the bit 125 centrally of its teeth when the teeth are engaged.

hammer on its down stroke when the teeth re-engage.

14. In a drill as set forth in claim 13, said ratchet teeth being annularly arranged, and **5** a reduced end on the hammer disposed centrally of its teeth adapted to engage the bit centrally of its teeth when the teeth are engaged.

15. In a drill as set forth in claim 13, said **10** compressible member comprising a coiled spring above the end of the hammer within the cap.

16. In a drill as set forth in claim 13, said **15** compressible member comprising a compressible fluid chamber above the end of the hammer within the cap; a stem on the chamber extending through cap; and a valve in said stem.

17. A rotary hammer drill, comprising a **20** drill bit having a bore; a cylindrical casing secured to the upper end of said bit; a pipe extending upwardly through the casing and fixed in the bore; a cylindrical hammer around the pipe and slidably and rotatably **25** mounted within the casing; a cap around said pipe and around the upper end of said hammer having a splined engagement with the hammer; a bearing in the upper end of said casing; said cap engaging the lower end of **30** the block to prevent separation of the cap and drill bit; a drive pipe for rotating the cap; said drive pipe extending down through the bearing; a tapered shoulder on said pipe engaging a tapered bearing seat in the bearing **35** for supporting the weight of the drive pipe; the upper end of the fixed pipe entering the lower end of the drive pipe; a compressible member within the cap; and normally engaging ratchet teeth on the bit and **40** hammer for rotating by friction the bit with the hammer, and for permitting overrunning of the hammer teeth upon restrained rotation of the drill bit to raise the hammer and compress the compressible member, thereby **45** augmenting the weight of the hammer on its down stroke when the teeth re-engage.

18. In a drill as set forth in claim 17; said ratchet teeth being annularly arranged, and **50** a reduced end on the hammer disposed centrally of its teeth adapted to engage the bit centrally of its teeth when the teeth are engaged.

19. In a drill as set forth in claim 17, said **55** compressible member comprising a coiled spring above the end of the hammer within the cap.

20. In a drill as set forth in claim 17, said compressible member comprising a compressible fluid chamber above the end of the hammer **60** within the cap; a stem on the chamber extending through cap; and a valve in said stem.

GUSTAVS ADOLPHIS BILLSTROM.
